CONVECTION HEATING RADIATOR

Russell C. Reichart, New York, N.Y.

Application January 21, 1932. Serial No. 587,923

8 Claims. (Cl. 257—124)

This invention relates to improvements in heating devices, more particularly to a radiator unit designed for heating by convection while at the same time also employing to a limited extent the principles of conduction and radiation, the object of the invention being to provide a simple, efficient and inexpensive convection heater for use with steam, hot water or vapor.

10 A further object of the invention is the provision of a radiator of more ornamental appearance and in which the size is considerably reduced while at the same time the efficiency thereof is increased.

15 It has heretofore been the practice to make radiators entirely out of cast iron employing the principles of radiation and convection, because of the long life thereof while it is a well known fact that copper, because of its high conductivity of heat, is more preferable except for the fact that there is a question of the life of copper when in contact with the necessary heating media such as steam etc., and therefore, a further object of the present invention 20 is the provision of a radiator using cast iron for conducting the heating media and copper or other highly conductive material for the major part of heating surface.

25 In the drawing accompanying and forming a part of this specification Fig. 1 is a top view of this improved convection heating device;

Fig. 2 is a longitudinal sectional side view thereof;

Fig. 3 is an enlarged cross sectional view taken 30 on the line 3—3 of Fig. 2; and

Fig. 4 is a perspective view of one of the copper fins used in this convection heater to radiate the heat.

35 Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawing since the invention is capable of other embodiments, and that the phraseology which I employ is for the purpose 45 of description and not of limitation.

The present improvement comprises a cored casting 2 of cast iron or other durable material designed to carry the heating media. This casting 2 comprises two or more hollow side sections 3 having tapered inner walls 4 and hollow

end sections 5 of the same material which serve as manifolds for the side sections 3.

At one end as at 6 is an inlet for the steam or other heating media while at the other end is an outlet 7.

Between the sections 3 a plurality of corrugated fins of wedge shaped formation are attached. These fins are tapered to fit the inner walls 4 of the sides 3 and are flanged on either side thereof as at 8 to insure thermal contact with the sides 4 to which they may be also attached if necessary by some chemical means such as solder. They may be made of copper or other highly conductive material and are corrugated to take up the expansion and contraction of the metal.

These copper fins are of very light material and are wedge shaped to securely fit within and between the tapered faces 4 of the sides 3, the wedge shape formation thereof serving to prevent their falling through the bottom and also to have a larger surface at their tops because of the greater expansion of the heated air at that point. The open bottom of the heater permits the air to enter at a temperature of approximately seventy degrees (70°) and become heated as it rises between the hot corrugated plates to approximately one hundred and forty degrees (140°) when it reaches the top of the heater and thus as it rises from the heater and mixes with the air of the room it serves to heat the same. This increased area at the top also serves to decrease the friction.

The corrugations prevent the thin plates from buckling as they expand upon being heated as would be the case if they were entirely straight and because of their extreme light weight they will readily contract and expand as an accordion rather than buckle.

Between the sides supporting webs such as 9 may be placed at intervals as desired for reinforcing the casing.

While copper is a highly conductive material it has never been proved successful as a radiator because it is soft and not durable, is easily distorted and no data is available on corrosion when in contact with the heating media. In this improved heater the outside casing is entirely of cast iron or some other proved metal while the inside structure is of copper thereby permitting the use of a highly conductive metal for heating purposes and a proved metal for conducting the heating media. The media enters the cast casing 2 by means of the inlet 6 passing through the manifold 5 and then around through the two

sides 3 to the manifold at the opposite end and thence out through the outlet pipe 7.

The circulation of this heating media through the sides 3 heats the casing by means of convection currents and the copper fins being wedged within the sides 4 gives a good thermal contact thus permitting them to become quickly and easily heated by conduction and they in turn transmit the heated air by convection to the room.

Thus it will be seen that I have constructed a new and highly efficient convection heating radiator which utilizes metal highly conductive in nature in combination with proved metal which will not corrode rapidly in such manner that the heating media never comes in contact with the light material thus preventing corrosion thereof. The strong outer casing also serves as a protector to this light metal thereby eliminating distortion and because of the high conductivity of the light weight metal a greater amount of effective heat may be transmitted to the room with less consumption of energy.

In practice some form of light weight material may be used as a cover for the heating device and this cover may be of ornamental design to add to the attractive appearance of the heating device.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A heating device comprising a casing composed of hollow side sections connected to manifolds at the ends thereof, the side sections spaced apart for the passage of air from bottom to top thereof, and a series of spaced corrugated fins of high conductive material secured within said space and extending substantially the entire distance from top to bottom of said side sections for forming a convection heater.

2. A heating device comprising a casing composed of hollow side sections for the passage of a heating media therethrough and connected to manifolds at the ends thereof, the side sections being spaced apart for the passage of air from bottom to top thereof and a series of spaced corrugated copper fins secured within said space

and extending substantially the entire distance from top to bottom of said side sections for forming a convection heater.

3. A heating device comprising a cast casing composed of hollow side sections for the passage of a heating media therethrough and connected at the ends thereof to manifolds, the side sections being spaced apart for the passage of air therebetween and having a downwardly tapering inner side wall, a series of wedge shaped copper fins wedged within said space for forming a convection heater.

4. A heating device comprising a cast casing composed of hollow side sections for the passage of a heating media therethrough and connected at the ends thereof to manifolds, the side sections being spaced apart for the passage of air therebetween and having a downwardly tapering inner side wall, and a series of corrugated wedge shaped copper fins wedged within said space and extending substantially the entire distance from top to bottom of said side sections for forming a convection heater.

5. A heating device comprising a pair of hollow sides having downwardly tapering inner side walls spaced apart to form an opening therebetween for the passage of air, and having hollow ends forming manifolds and forming a casing for the passage of a heating media, and a series of spaced corrugated light weight copper wedge shaped fins wedged between said side sections and extending substantially the length of said sides for forming a convection heating radiator.

6. A heating device comprising a rectangular cored cast casing, for the passage of a heating media having an air space interiorly of said casing, and a series of wedge shaped corrugated fins secured within said space to the inner sides of said casing for the conduction of heat thereto thereby to heat the air within said space thereby forming a convection heating radiator.

7. A cast iron heating device having spaced hollow side sections provided with inner downwardly tapering side walls and wedge shaped fins of high conductive material located between said tapering walls.

8. A cast iron heating device having spaced hollow side sections provided with inner downwardly tapering side walls and corrugated wedge shaped fins of high conductive material located between said tapering walls and extending substantially the length of said walls.
